UNITED STATES PATENT OFFICE.

CHARLES L. FARNSWORTH, OF DETROIT, MICHIGAN.

BUTTON-FASTENER.

SPECIFICATION forming part of Letters Patent No. 280,730, dated July 3, 1883.

Application filed April 18, 1883. (No model.)

To all whom it may concern:

Be it known that I, CHARLES L. FARNSWORTH, of Detroit, county of Wayne, State of Michigan, have invented a new and useful Improvement in Button-Fasteners; and I declare the following to be a full, clear, and exact description of the same, such as will enable others skilled in the art to which it pertains to make and use it, reference being had to the accompanying drawings, which form a part of this specification.

My invention consists in the button-fastening device hereinafter described, and more particularly pointed out in the claim.

In the drawings, Figure 1 is a side elevation of a device embodying my invention. Fig. 2 is an end view of the same. Fig. 3 is a plan view. Fig. 4 represents the device with a button in process of insertion. Fig. 5 presents views illustrating the action of the fastener upon the foot.

The object of my invention is to provide an adjustable fastener adapted to secure buttons firmly upon shoes, gloves, and general clothing without injury to the fabric, which may be readily disengaged from the button and the fabric, and again adjusted therein whenever it may be desired. I accomplish this result by constructing a fastener of one continuous piece of spring-wire, bent in a suitable shape to form a firm flat surface to constitute a brace or guard for the under surface of the leather or other fabric, the two ends being then twisted about each other and bent upward perpendicular to the base into hooks standing side by side, but turned in opposite directions, said hooks separating readily down to the twist at the base of the shank, said shank adapted to pass through a single hole in the fabric.

In carrying out my invention, A represents the base or guard of the fastener, constructed of spring-wire bent into any suitable form, preferably resembling a figure 8.

B and B' represent the shank of the fastener, constructed of the two ends of the continuous piece of wire bent upward perpendicular to the base, and twisted about each other, as shown at b. A quarter-twist I find to effect a very good purpose; but it brings the plane

of the hooks perpendicular to the length of the base, and I therefore prefer a half or a full twist—in other words, such a twist as shall unite the wires firmly at the base of the shank and leave the plane of the hooks in the direction of the length of the base. The two ends of the wire are each terminated in a hook, C and C', standing side by side, the hooks being turned in opposite directions and free at their lower ends.

D is the fabric. E is the eye of the button.

It is evident that the shank B and B' is adapted to pass through a single hole in the fabric, and that by pressing the eye of the button between the two hooks C and C' it may be readily engaged therewith. It is also evident that the eye of the button may be readily disengaged from the hooks of the fastener without impairing the same. In this manner the button can be removed and readjusted, as may be desired.

It is obvious that the under surface of the fastener will form an easy-setting guard when worn upon the person.

I am aware that a button-fastening has been made of a solid flat plate of metal having oppositely-hooked arms projecting from its opposite sides, and bent back toward each other, and projecting side by side from the surface of the plate, so as to form a shank to engage the eye of the button; but I do not claim a fastening so constructed. It is obvious that such a fastening cannot have the strength and durability of a fastening made of a spring-wire in the manner herein described. Moreover, the open base of my device allows it to yield more readily and accommodate itself to the person.

I am also aware that various devices have been made of wire, and that a single piece of wire has been formed into an open base or guard, the two ends then bent perpendicular to the base and terminated in hooks turned in opposite directions; nor do I claim a fastening so constructed, as such a device does not have the shanks twisted about each other. I have discovered that such a twist as I have described is quite essential to the efficiency of the fastening. The twist keeps the fastening from springing apart after the button is en-

gaged therewith. It also prevents the hooks from opening below the base of the shanks. Without the twist the button is liable to work loose, and the base is almost surely sprung 5 open and permanently distorted by inserting the button-loop; but by my improvement the shank of the outer shank of the fastener is made firmer and holds the shank in the eye of the button without liability of accidental displacement, and with no danger of 10 distorting the base, as above explained. The twist causes a firmer spring to the shank, and thereby makes the fastening stronger and more reliable. So, also, when the shank goes straight up from the base without the twist, 15 the hooks, after the fastening has been used for a while, are apt to slide past each other in their own plane, thus rendering the device insecure. By my device this difficulty is entirely remedied. Moreover, the twist permits 20 the fabric to come in closer to the shank of the fastener, diminishing the size of the hole required in the fabric. Moreover, the twisting of the shanks so their plane shall stand 25 at right angles or across the length of the base, as I have described to be preferable, prevents the tilting of the base and consequent hurting of the foot or person. If the hooks extend in the direction of the width of the base, when

applied, for instance, to a shoe, the base would naturally rest lengthwise of the foot, as shown 30 at *a* in Fig. 5, and the strain of the button would cause the base to roll over and its edge 35 to irritate the foot. By giving the extremities, however, a sufficient twist to bring the hooks into the direction of the length of the base, as shown at *a'* in Fig. 5, the 8-shaped base lies in a direction across the foot, and thus affords a greater leverage against any tilting action, and so is easier upon the foot. 40

What I claim is—
As an improved article of manufacture, the herein-described button-fastener, consisting of a single piece of wire bent to form a base, with its extremities twisted about each other over the base after the same is formed, said extremities beyond the twist terminating in hooks, which stand side by side with their ends turned in opposite directions, substantially as described. 45

In testimony whereof I sign this specification in the presence of two witnesses:

CHARLES L. FARNSWORTH.
